UNITED STATES PATENT OFFICE.

ALBERT T. FISCHER, OF CLEVELAND, OHIO.

DESIGN FOR A BADGE.

No. 39,737.

Specification for Design.

Patented Jan. 5, 1909.

Application filed September 18, 1908. Serial No. 453,697. Term of patent 7 years.

To all whom it may concern:

Be it known that I, ALBERT T. FISCHER, a citizen of the United States, residing at Cleveland, in the county of Cuyahoga and State of Ohio, have invented a new, original, and ornamental Design for a Badge, reference being had to the accompanying drawings, forming part thereof.

The figure is a plan view of a badge showing my new design.

What I claim is:

The ornamental design for a badge, as shown.

ALBERT T. FISCHER.

Witnesses:

H. T. FISHER,
E. M. FISHER.
